CLAIM

The ornamental design for a tooth pick with dental floss holder, as shown and described.

DESCRIPTION

FIG. 1 is a perspective view from above and one end of a toothpick with dental floss holder showing my new design;

FIG. 2 is a perspective view of the toothpick with dental floss holder from below and the opposite end thereof;

FIG. 3 is a front elevational view thereof, the opposite view being a mirror image thereof;

FIG. 4 is a right side elevational view thereof;

FIG. 5 is a left side elevational view thereof;

FIG. 6 is a top plan view thereof; and,

FIG. 7 is a bottom plan view thereof.
